DESIGN FOR A PROJECTOR

Maurice H. Goldberg, Chicago, Ill., assignor to
Isreal J. London, Laura London, and Burton W.
London, all of Detroit, Mich., as joint tenants
with right of survivorship

Application August 14, 1939, Serial No. 86,657

Term of patent 3½ years

To all whom it may concern:

Be it known that I, Maurice H. Goldberg, a citizen of the United States, residing at Chicago, county of Cook, and State of Illinois, have invented a new, original, and ornamental Design for a Projector, of which the following is a specification, reference being had to the accompanying drawings, forming a part thereof.

In the drawings,

Figure 1 is a top plan view of the projector showing my new design;

Figure 2 is a side elevational view of the projector;

Figure 3 is a front elevational view of the projector; and

Figure 4 is a rear elevational view thereof.

I claim:

The ornamental design for a projector, substantially as shown.

MAURICE H. GOLDBERG.
